CLAIM

The ornamental design for a bracket assembly as shown and described.

DESCRIPTION

FIG. 1 is a perspective view of a bracket assembly, including a top plate and a bottom plate;

FIG. 2 is a front view of the bracket assembly of FIG. 1.

FIG. 3 is a back view of the bracket assembly of FIG. 1.

FIG. 4 is a right side view of the bracket assembly of FIG. 1.

FIG. 5 is a left side view of the bracket assembly of FIG. 1.

FIG. 6 is a top side view of the bracket assembly of FIG. 1.

FIG. 7 is a bottom side view of the bracket assembly of FIG. 1; and,

FIG. 8 a perspective view of the bracket assembly supporting a display.

The dash-dash broken lines shown in the drawings depict portions of the bracket assembly that form no part of the claimed design. The linear shade lines represent contours only and do not illustrate ornamentation or decoration on the surface of the bracket assembly.
